United States Patent Office.

ALBERT P. SEYMOUR, OF HECLA WORKS, NEW YORK.

Design No. 4,238, dated July 19, 1870.

DESIGN FOR A MATCH-SAFE.

The Schedule referred to in these Letters Patent and making part of the same

To all whom it may concern:

Be it known that I, ALBERT P. SEYMOUR, of the Hecla Works, in the county of Oneida and State of New York, have invented a new and original Design for a Match-Safe, of which the following is a specification.

Nature of my Design.

My design relates to making the front of a match-safe of six sides, four of which are of a rectangular shape, and two of a triangular shape, arranged as hereinafter described.

Description of Accompanying Drawings.

Figure 1 is a front elevation of my match-safe.

Figure 2 is a cross-section, through the center of same.

Figure 3 is a top view of same.

General Description.

K, see fig. 1, is the back of the match-safe.

A, B, and O, are each rectangular sides, forming the upper portion of said safe.

A is parallel with the back K.

B and O extend from the side edges of A, obliquely to the back K.

D is a rectangular side, extending from the lower edge of A obliquely downward to the back K.

E and H are each rectangular triangular sides, joined to the side edges of D, and also to the lower edges of B and O, and extending obliquely back to K.

A, B, O, and D, may be rectangles, or be of a rectangular shape.

E and H may be exact triangles, or of a triangular shape.

Claim.

What I claim as my invention, and desire to secure by Letters Patent, is—

A design for a match-safe, the upper and principal part of whose front is composed of three sides, of a rectangular shape, and the lower and subordinate part of said front of one side, of a rectangular shape, and also of two sides of a triangular shape, substantially as described and represented.

Witnesses: ALBERT P. SEYMOUR.
